FIG. 6.

Inventor:
Sam Dow,
by his attorney,
Preston S. Gooding.

UNITED STATES PATENT OFFICE.

SAM DOW, OF BOSTON, MASSACHUSETTS.

DETACHABLE RUBBER HEEL FOR SHOES.

1,397,834.

Specification of Letters Patent.

Patented Nov. 22, 1921.

Application filed May 26, 1920. Serial No. 384,299.

To all whom it may concern:

Be it known that I, SAM Dow, a subject of Syria, residing at Boston, in the county of Suffolk and State of Massachusetts, have 5 invented new and useful Improvements in Detachable Rubber Heels for Shoes, of which the following is a specification.

This invention relates to heels for boots and shoes and is especially adapted for use 10 in connection with heels, the body portion of which is made of wood or metal.

The object of the invention is to provide a tread for the heel of a boot or shoe which can be easily attached to or detached from the 15 body portion of the heel of the shoe without the use of nails or without the use of adhesive material of any kind and which, when attached to the body portion of the heel, cannot become accidentally detached therefrom, 20 but which can be so manipulated as to become detached by hand for the purpose of attaching a new tread to the bottom portion of the heel when said tread has become worn or otherwise injured.

25 The invention consists in a heel with a resilient tread and means for detachably attaching the tread to the heel as hereinafter set forth in the specification and particularly pointed out in the claim.

30 Referring to the drawings:

Figure 1 is a side elevation, partly in section, of my improved heel.

Fig. 2 is an end elevation of the same broken away and partly in section on line 35 2-2 of Fig. 1.

Fig. 3 is a sectional elevation similar to Fig. 1 illustrating the manner in which the parts are positioned when the tread is being attached to the heel.

40 Fig. 4 is a sectional elevation similar to Fig. 1 showing the relative positions of the parts when the tread is being detached from the heel.

Fig. 5 is a detail plan view of the dove-tailed slide plate whereby the tread is attached to the body portion of the heel.

Fig. 6 is a detail plan view of the plate which is molded in the tread and is slidable upon the dove-tailed plate illustrated in 50 Fig. 5.

Like numerals refer to like parts throughout the several views of the drawings.

In the drawings, 8 is the body portion of the heel which may be made of wood, aluminum or any suitable material. A slide plate 55 9 is fastened by a screw 10 to the bottom of

the body portion 8, this slide plate having beveled edges 11 which are beveled downwardly and outwardly from the bottom surface of the body portion 8. 12 is the tread 60 of the heel made of resilient material, preferably rubber, and in this tread is embedded a plate 13 which has flanges 14 on its upper surface inclined toward each other and adapted to slide upon the beveled edges 11 65 of the slide plate 9. The plate 13 extends on its opposite sides beyond the flanges 14 within the rubber tread 12, whereby it is anchored in said tread.

It will be noted that the upper edges of 70 the flanges 14 are flush with the upper surface of the tread 12.

The tread is attached to the shoe by tipping it at an angle, as illustrated in Fig. 3, and pressing the upper surface of the tread 75 adjacent the rear portion thereof against the bottom of the body portion of the heel and against the bottom of the slide plate 9 to compress that portion of the tread sufficiently to allow the plate 13 to engage the 80 slide plate 9 and the flanges 14 thereon to be brought into alignment with the beveled edges 11, whereupon the tread is slipped upon the body portion of the heel with the plate 13 sliding on the slide plate 9 and the 85 flanges 14 engaging the beveled edges 11 of the slide plate 9.

When the tread has been pushed along the bottom of the heel from the breast of the heel toward the back of the heel to the 90 position illustrated in Fig. 1, it will be seen that the tread is locked against movement across the heel by the flanges 14 and slide plate 9. It will also be seen that it is locked against movement longitudinally of the heel 95 and longitudinally of the slide plate 9 by the portions 15 and 15' of the tread, each of which is in horizontal alignment with the slide plate 9, and, therefore, the tread will be locked to the body portion of the heel 100 against longitudinal movement relatively to the slide plate 9, as well as against movement across the heel. In removing the tread from the body portion of the heel, the portion 15' of the tread is bent downwardly 105 either by hand or by inserting a thin metal piece such as a screw-driver between the top of the portion 15' of the tread and the bottom of the body portion of the heel at the rear thereof, thus causing the tread to assume the position illustrated in Fig. 4, whereupon the tread may be removed from

the shoe by sliding the same forwardly, the plate 13 at this time sliding upon the slide plate 9 until it becomes detached therefrom.

I claim:

5 A heel for boots and shoes having, in combination, a body portion having an uninterrupted flat surface, a dove-tailed slide plate with parallel sides fast to the bottom of said body portion, a rubber tread for said heel and an imperforate plate embedded in 10 said tread and locked therein, said rubber forming shoulders at the opposite ends of said imperforate plate and said imperforate plate having a pair of parallel flanges inclined toward each other and adapted to 15

slide upon said slide plate and engage said parallel sides, the upper edges of said flanges being substantially flush with the upper face of said tread, said plates being prevented by the engagement of said shoulders with the opposite ends of said slide plate from relative movement longitudinally thereof when the parts are assembled.

In testimony whereof I have hereunto set my hand in presence of two subscribing witnesses.

SAM DOW.

Witnesses:
